CLAIM

The ornamental design for a speaker as shown and described.

DESCRIPTION

FIG. 1 is a perspective view of a speaker showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top end plan view thereof; and,

FIG. 8 is a bottom end plan view thereof.

The broken lines depict non-claimed portions of the speaker that form no part of the claimed design.

1 Claim, 6 Drawing Sheets(56)
